UNITED STATES PATENT OFFICE

94,067

DESIGN FOR A FOOD CONTAINER OR SIMILAR DEVICE

Charles C. Beam, Pittsburgh, Pa.

Application November 30, 1932, Serial No. 46,203

Term of patent 7 years

To all whom it may concern:

Be it known that I, Charles C. Beam, a citizen of the United States, residing at Pittsburgh, Pennsylvania, have invented a new, original, and ornamental Design for a Food Container or Similar Device, of which the following is a specification, reference being had to the accompanying drawing, forming part thereof.

The drawing shows in perspective a food container showing my new design and with the two lower trays partially withdrawn, although the invention is not limited with respect to the positions of the trays.

I claim:

The ornamental design for a food container or similar device substantially as shown and described.

CHARLES C. BEAM.
